FLUID HEAT EXCHANGE APPARATUS

Kenneth Napier, Barberton, Ohio, assignor to
The Babcock & Wilcox Company, Newark,
N. J., a corporation of New Jersey

Application May 4, 1933, Serial No. 669,285

49 Claims. (Cl. 122—6)

This invention relates to furnace wall construction used in fluid heat exchange apparatus.

One object of the invention is the provision of blocks which may be used in a continuous series 5 to close the spaces between fluid conducting tubes in a furnace wall.

Another object is the provision of such blocks in a form which will permit them to be placed in position along a furnace wall by insertion 10 between the support members or water tubes from without the furnace.

A further object is the provision of means for mounting block units to produce pressure between the parts forming the unit and the tubes 15 in order to hold the block units firmly in place, and yet permit the removal of blocks when it is desired to replace them without requiring disturbance of the entire wall or even adjacent units. Other object will appear upon consideration 20 of the present specification.

In the accompanying drawings:

Fig. 1 is a side elevation of a portion of a furnace wall embodying the invention,

Fig. 2 is a front elevation of the wall illustrated 25 in Fig. 1 viewed from the inside of the furnace.

Fig. 3 is a section on the line III—III of Fig. 2,

Fig. 4 is a rear view in elevation of a portion of 30 the wall shown in Fig. 2,

Fig. 5 illustrates the invention applied to tubes 35 which are curved in a concave sense with respect to the furnace interior,

Fig. 6 illustrates the invention applied to tubes which are curved in a convex sense with respect 40 to the furnace interior,

Fig. 7 is a perspective view of one of the wall 45 blocks,

Fig. 8 is a detail view showing successive steps in the formation of the furnace wall built according to the present invention,

Fig. 9 is a detail elevation showing two wall 50 block parts in an intermediate position, and—

Fig. 10 is a detail front elevation of a wall section.

The furnace wall as it is shown in the drawings 55 consists of a row of fluid conducting tubes 10 and interposed wall elements or blocks 12 which are of heat resisting material. In the present case they are of metal. The blocks are preferably carried by the tubes and are arranged thereon to form a substantially closed furnace wall. When a suitable insulation material or refractory material covers the blocks a complete furnace wall will be formed. The interior or fire side of this wall is illustrated in Fig. 2 of the drawings. The wall may be made air tight

by the addition of packing material inserted between adjacent blocks or between adjacent tubes or by plastic insulation applied to the outside of the structure.

In order that the wall blocks may be placed in their operative positions from points exterior of the furnace walls or the rows of tubes as indicated in Figs. 8, 9 and 10, they are formed as hereinafter described. The inner end 24 of each block is of such a dimension that it may be inserted between two adjacent tubes 10 when the block is turned to the position indicated in the left hand part of Fig. 8 of the drawings. In this position the block is substantially 90° removed from its operative position in which it forms a 15 part of the completed furnace wall. After the inner end of the block is passed beyond the center line of two adjacent tubes as indicated in the intermediate part of Fig. 8, the block is turned to the position indicated at the right hand 20 part of that figure. Further turning of the block brings it to the position in which it is indicated in Fig. 9 of the drawings.

After two complementary blocks are brought into position as indicated in Fig. 9 of the drawings, a tension member 16 is passed through corresponding openings 18 in the heel or outer portion 20 of each element, and a resilient member 21. Thereafter a nut 22 tightened on the tension member 16 against the member 21 brings the 30 two complementary blocks into wall closing positions with the blocks resiliently held against the tubes so that expansion does not decrease the quality of the heat transfer contact between the tubes and the blocks. The illustrated blocks thus 35 permit the assembly or repair of the furnace wall from points without the furnace. A workman need not go into the furnace to place the wall blocks in position. This is an important 40 advantage especially in the repair of furnace walls before the furnaces are completely cooled, or when the structure is located in a position as for example adjacent boiler tubes so as to make it inaccessible from the inside of the furnace. 45

As clearly indicated in Figures 3, 7, and 8 of the drawings each wall block has an inner portion or face 24 joined with an outer portion 20 by a narrow intermediate section bounded by curved faces 26 fitting tightly against the tubes 50 in the completed wall structure. The face 24 rests against the furnace sides of the tubes and is presented toward burning fuel in the furnace. This intermediate section may be termed a bout. It is reinforced by an external flange or rib 28 55

extending to a base which forms the stud 30 around the opening 18.

When the wall elements are in their operative positions, the outer portions 20 form strong reinforcing ribs or flanges as clearly indicated in such figures as Fig. 4. These ribs extend transversely of the tubes as shown and operate to materially stiffen the entire wall structure and maintain the tubes in their spaced relationships. The inner portions or faces 24 form strengthening ribs which extend across the inner sides of the tubes as indicated in Figs. 1 and 2. The faces 24 of some of the adjacent blocks or wall elements may contact with each other as indicated in Fig. 1.

When the wall elements are in their operative positions as indicated in Fig. 1 of the drawings adjacent elements extend convergently outwardly of the wall so as to form pockets in which refractory material may be held. Such material, whether in the form of slag deposited from burning fuel, or in the form of a refractory layer which is manually placed over the wall, may cover the portions of the tubes which are not covered by the wall elements themselves. Preferably, the blocks or wall elements are formed with studs 32 shown as extending in directions normal to the outwardly converging faces of the blocks. These studs, however, are not employed when the blocks are not covered.

As shown the blocks are formed on their inner sides with ribs 34 which preferably contact with each other when the blocks are being brought into their operative relations with the tubes. Referring again to Fig. 9 of the drawings, after the two blocks there shown are moved slightly towards each other, the ribs 34 will contact and form in effect a fulcrum about which the blocks are turned as they are being tightened against the tubes by tension applied by the members 16 and the nuts 22 thereon. The ribs 34 also operate to form, with the tubes and the studs 32 additional pockets in which refractory material may be positioned.

The illustrative wall blocks are of such form that they may readily form a complete furnace wall, even where the wall is supported by curved tubes as indicated in Figs. 5 and 6 of the drawings. They are as adaptable for forming a part of the furnace wall which is convex towards the interior of the furnace as well as they are upon the wall which is concave towards the interior of the furnace.

Besides presenting the advantage of permitting the wall blocks to be placed from positions exteriorly of the furnace, the illustrative embodiment of the invention presents an additional important advantage in that all of the wall block elements may be of the same formation. This promotes considerable economies in the assembly and repair of furnaces, reducing the variety of parts which must be kept on hand for furnace repair.

While the invention has been described with reference to the particular embodiment shown in the drawings, it is to be understood that the invention is not limited thereto but is of a scope commensurate with the scope of the sub-joined claims.

What is claimed is:

1. In a furnace wall, spaced wall cooling tubes, closure members mounted upon the tubes for closing the spaces between the tubes, and tension members each exerting a force in a direction parallel to the longitudinal axes of the tubes for holding said members in contact with the tubes.

2. In a furnace wall, spaced wall cooling tubes, wall blocks or closure members insertable between the tubes from the exterior of the furnace and contacting with the tubes along spiral lines when in their operative positions, and tension members exerting their forces in directions parallel to the longitudinal axes of the tubes to hold the blocks against the tubes so as to have a heat transfer relation therewith. 5

3. In a furnace, a row of spaced fluid conducting tubes delineating a furnace wall, coating wall blocks of identical construction having parts extending across the inner and outer sides of the tubes and forming with the tubes a substantially continuous and complete furnace wall, and means engaging the parts of the wall blocks extending across the sides of the tubes remote from the interior of the furnace to exert pressure on those parts to bring intermediate portions of the blocks into closely fitting contact 20 with the surfaces of the tubes extending from their furnace sides to their remote sides.

4. In fluid heat exchange apparatus, a row of fluid conducting tubes delineating a furnace wall, and wall blocks of identical construction each 25 engaging both the forward and rearward sides of the tubes with their parts engaging the rearward sides of the tubes constituting also a part of the furnace wall presented toward the interior of the furnace.

5. In a furnace wall, spaced substantially parallel support members, and a block unit for closing the space between said support members, said block unit comprising two parts of identical construction each having two substantially longitudinal concave surfaces for engaging the two adjacent support members forwardly and rearwardly of their center line, and means for mounting said unit to produce pressure between the surfaces on the parts and the support members. 30

6. In a furnace wall, spaced substantially parallel cylindrical support members, and a block unit for closing the space between said support members, said block unit comprising two parts of identical construction each having two substantially longitudinal concave surfaces for engaging the two adjacent support members forwardly and rearwardly of the common center line of the members, and means for mounting said unit to produce pressure between the surfaces on the parts and the support members. 45

7. In a furnace wall, spaced substantially parallel water tubes, and a block unit for closing the space between said tubes, said block unit comprising two parts of identical construction each having two substantially longitudinal concave surfaces for engaging the two adjacent tubes forwardly and rearwardly of their center line, and means for mounting said unit to produce pressure between the surfaces on the parts and the tube. 50

8. A furnace wall comprising spaced vertical water tubes, block units insertable between said tubes from outside the furnace for closing the spaces between the tubes, each block unit comprising two identical parts disposed one above the other when in position between said tubes, and means for mounting said unit to produce pressure between the parts and the tubes. 65

9. A furnace wall comprising spaced parallel vertical water tubes; and a series of block units closing the spaces between said tubes; each block unit comprising two parts each having two longitudinal concave surfaces for contact with the two adjacent tubes forwardly and rearwardly of their 75

center line, a rearwardly extending flange, and nut and bolt means coacting with the flanges on each part comprising a block unit for mounting said unit to produce pressure between the surfaces on the parts and the tubes, substantially as described.

10. In a furnace construction a row of spaced fluid conducting tubes, furnace wall elements of similar construction contacting with the tubes and forming therewith a substantially complete wall or furnace gas boundary, and tension means positioned on the exterior side of the row and acting against adjacent parts of two of said elements to cause them to be clamped against the adjacent tubes, each wall element having a part which closely fits the tubes across their furnace sides and another part which closely fits the tubes across the other sides remote from the interior of the furnace.
20. 11. In a furnace, a plurality of spaced fluid conducting tubes outlining a wall, wall blocks of similar construction insertable between the tubes from the exterior of the furnace and having parts extending along the inner and outer sides of the tubes to complete the furnace walls and substantially close the spaces between the tubes, and tension means acting upon portions of adjacent wall elements to cause them to tightly grip the tubes so that they are held in position thereby.
30. 12. In a furnace wall, spaced wall cooling tubes, closure members mounted upon the tubes for closing the spaces between the tubes, tension members each exerting force in a direction parallel to the longitudinal axes of the tubes for holding said members in contact with the tubes, and resilient members coacting with the closure members to maintain them resiliently pressed against the tubes.
40. 13. In a furnace wall, spaced wall cooling tubes, wall blocks or closure members insertable between the tubes from the exterior of the furnace and contacting with the tubes along spiral lines when in their operative positions, tension members exerting their forces in a direction parallel to the longitudinal axes of the tubes to hold the blocks against the tubes so as to have a heat transfer relation therewith, and resilient members coacting with the tension members and the closure members to maintain the latter resiliently pressed against the tubes under all conditions of expansion and contraction.
50. 14. In a furnace wall, spaced wall cooling tubes, closure members mounted upon the tubes for closing the spaces between the tubes, and tension members each exerting force in a direction parallel to the longitudinal axes of the tubes for holding said members in contact with the tubes, all of said closure members being of identical construction and constituting the only wall forming members in contact with the tubes.
60. 15. In a furnace wall, spaced wall cooling tubes, wall blocks or closure members insertable between the tubes from the exterior of the furnace, tension members exerting their forces in a direction parallel to the longitudinal axes of the tubes to hold the blocks against the tubes so as to have a heat transfer relation therewith, and resilient devices interposed relative to the tension members and the closure devices.
70. 16. In a furnace wall, spaced wall cooling tubes, double concave closure members obliquely mounted upon and between adjacent tubes for closing the spaces between the tubes, tension members each exerting a force along the wall for clamping said members on the tubes, and resilient mem-

bers coacting with the tension members to maintain the closure members resiliently pressed against the tubes.

17. In a furnace wall, spaced wall cooling tubes, metallic wall blocks or closure members of identical construction insertable between the tubes from the exterior of the furnace and contacting with the tubes along spiral lines when in their operative positions, tension members exerting their forces along the tubes to hold the blocks against the tubes so as to have a good heat transfer relation therewith, and resilient members coacting with the tension members and the closure members to maintain the latter resiliently pressed against the tubes under all conditions of expansion and contraction.

18. A double concave furnace wall block with its concave sides each bounded by a surface extending along a helical curve and adapted to fit tightly against a tube when the block is arranged obliquely with reference to the longitudinal axis of the tube.

19. A double concave furnace wall block with its curved sides constituting parts of tube fitting helices adapted to fit tightly against cylindrical tubes when the block is arranged obliquely thereto.

20. A metallic double concave furnace wall block having its opposite sides bounded by tube fitting surfaces which are parts of helices when the block is arranged obliquely relative to the tube.

21. In combination with furnace wall tubes, a double concave metallic furnace wall block comprising, a clamping part, an inner tube engaging part adapted to be disposed transversely of furnace wall tubes along their furnace sides, and a double concave intermediate part connecting the above indicated parts and bounded on opposite sides by surfaces which are adapted to fit tightly against adjacent tubes and constitute parts of tube enclosing surfaces in the nature of helices.

22. In a furnace wall, wall tubes, pairs of blocks shaped to fit the tubes when oblique to the tubes with the blocks of each pair diverging, and means acting on the blocks to change their obliquity and thereby cause the blocks to be clamped against the tubes, the blocks completing the furnace wall closure when clamped in position.

23. In a furnace, spaced tubes, metallic wall units having inner and outer sections positioned on opposite sides of the tubes and connected by sections oblique to the tubes, and means acting on the outer sections to cause the units to be bound against the tubes, the units being insertable between adjacent tubes from a position exteriorly of the furnace.

24. In the furnace art, the method of building a furnace wall comprising arranging spaced tubes in wall delineating relationship, inserting wall elements between the tubes from positions exteriorly of the furnace, turning those elements to interlock them with the tubes, and pivoting the blocks on a transverse axis, then exerting pressure on the elements to further pivot them and thereby bind them into good heat exchange relationship with the tubes.

25. A furnace wall structure for closing the spaces between adjacent tubes comprising, an inner portion constructed and arranged to bridge the space between two wall tubes and to have its rearward side fit against the front parts of those tubes, an outer clamping part constructed and arranged to receive pressure to cause the structure to pivot and to be clamped against the tube,

a narrow intermediate double concave part connecting the above described parts and bounded at its opposite sides by surfaces which closely fit against the sides of two adjoining tubes when the structure is oblique thereto, and a fulcrum portion intermediate the ends of the structure constructed and arranged to contact with another similar structure and to cause the first structure to be pivoted and brought into good heat exchange relationship with the tubes upon the application of pressure to said outer part.

26. Furnace wall elements of identical construction constructed and arranged to close the spaces between wall cooling tubes and consisting of end portions connected by double concave mid-portions having their opposite sides inwardly and helically curved to form parts of cylindrical surfaces having their axes oblique to the mid-portions to fit tightly against wall tubes when the elements are positioned obliquely with reference to the longitudinal axes of the tubes, the mid-portions being narrower than said end portions.

27. A furnace wall block having wall forming end portions connected by a narrow double concave mid-portion defined at its opposite sides by concave tube fitting surfaces adapted to closely fit against a tube when the block is arranged obliquely thereto, one end portion of the block being insertible within the furnace between adjacent tubes and the other end portion having a flange against which a clamping force reacts to pivot the block and bind it tightly against a tube, the flange being oblique to the mid-portion.

28. In a fluid cooled furnace wall, a row of spaced tubes, blocks insertible between the tubes from positions exteriorly of the furnace, and means extending and acting longitudinally of the tubes and positioned exteriorly of the row of tubes for pivoting the blocks to bind them against the tubes, the blocks being arranged in pairs with the blocks of each pair fulcruming on each other as said means is operated and each block being replaceable without the displacement of any block other than the complementary block of its pair.

29. A furnace wall block formed with two separate helical and cylindrical tube engaging surfaces each with an axis oblique to the direction in which the block has its maximum dimension.

30. A metallic furnace wall block having a tube fitting portion and an inner end part forming furnace faces in front of the tube fitting portion, said portion also forming a furnace face facing in the same direction as the other furnace faces.

31. A furnace wall block having tube fitting portions on opposite sides of a fulcrum portion about which the block is pivotable on an axis transverse to the axes of adjoining tubes.

32. In a furnace, spaced tubes, unitary wall blocks individually bridging the furnace sides of adjacent tubes and being operatively positionable from positions exteriorly of the furnace, fulcrum parts on the blocks, and means acting on the blocks to pivot them on said fulcrum parts and about axes transverse to the longitudinal axes of the tubes to cause the blocks to be tightly clamped against the tubes.

33. In a metallic structural unit, transverse end portions connected by a relatively narrow intermediate portion, and a fulcrum forming projection, opposite sides of the intermediate portion having surfaces defined by straight line elements

all parallel to an axis oblique to said intermediate portion.

34. In a metallic furnace wall block, a relatively narrow intermediate portion connecting two transverse end portions which extend outwardly beyond both sides of the intermediate portion, and a fulcrum forming projection.

35. In a metal furnace wall block, a relatively narrow intermediate portion, end portions extending in the same plane beyond opposite sides of the intermediate portion, and a fulcrum forming portion extending from the intermediate portion in a direction at an angle to said plane.

36. In a furnace; spaced wall cooling tubes; and metallic structural units comprising, transverse end portions connected by relatively narrow intermediate portions which are obliquely related to one end portion in each unit, and fulcrum forming projections, opposite sides of the intermediate portions having surfaces defined by elements parallel to axes oblique to said intermediate portions; the end portions and projections being so constructed and arranged that while said units can be moved between the tubes to their operative positions from positions exteriorly of the furnace the units cannot be moved between successive tubes entirely to positions within the furnace.

37. A furnace wall comprising spaced tubes, and blocks arranged between and along successive tubes in zigzag formation to close the spaces between the tubes and complete the wall, the blocks presenting furnace faces both rearwardly and forwardly of the center lines of the tubes.

38. In a furnace wall, a row of spaced tubes, metallic wall blocks of similar construction arranged in pairs of oppositely angled blocks between successive tubes, the blocks of a pair having extensions converging toward a position exteriorly of the row of tubes, the blocks also having inner extensions or portions positioned over the sides of the tubes toward the interior of the furnace, and means reacting against the blocks to pivot them and cause both sets of extensions to be clamped tightly against the tubes.

39. A furnace wall comprising spaced tubes, and blocks arranged between and along successive tubes in zigzag formation relative to the plane of the wall to close the spaces between the tubes and complete the wall, adjacent blocks having refractory anchoring projections extending into wall pockets formed between the blocks and the tubes.

40. In combination, spaced furnace wall tubes, wall elements arranged in zigzag formation relative to the plane of the wall to close the spaces between the tubes, the elements having transverse end portions positioned on opposite sides of the tubes, and projections transversely related to the end portions and cooperating therewith for preventing the elements from passing entirely through the spaces between the tubes while permitting those elements to be placed in operative position from points beyond the tubes exteriorly of the furnace.

41. In a furnace of the type including spaced wall tubes connected into fluid circulation, blocks closing the spaces between the tubes and having body portions with double concave tube contacting surfaces each generated by a straight line element remaining constantly parallel to the longitudinal axis of a right cylinder while it moves in a helical path.

42. A block for spanning the space between two parallel tubes which comprises a body portion the

sides of which are of substantial width and shaped to lie along the tubes and in contact therewith throughout their width and at an angle between 90° and 180° with respect to the axis of the tubes.

5 43. Double concave furnace wall blocks having opposite tube fitting surfaces each generated by a straight line element constantly parallel to the longitudinal axis of a tube and moving in a path in the nature of a helix.

10 44. Furnace wall elements of identical construction adapted to close the spaces between wall cooling tubes and consisting of end portions connected by double concave mid-portions having opposite surfaces corresponding to exterior tube 15 surfaces positioned between two substantially parallel planes obliquely cutting two spaced and parallel tubes.

20 45. In combination with furnace wall tubes, a metallic furnace wall block having a tube fitting portion presenting furnace faces forwardly and rearwardly of the center lines of the tubes.

25 46. In a metallic structural unit having transverse end portions connected by a relatively narrow intermediate portion, opposite sides of the intermediate portion having curved surfaces in the nature of parts of helices defined by straight line elements all parallel to an axis oblique to said intermediate portion.

47. In a furnace; spaced wall cooling tubes; and

metallic structural units comprising, transverse end portions, and relatively narrow intermediate portions connecting the end portions, opposite sides of the intermediate portions having surfaces defined by elements parallel to axes oblique to said intermediate portions; the end portions and projections being so constructed and arranged that while said units can be moved between the tubes to their operative positions from positions exteriorly of the furnace the units 10 cannot be moved between successive tubes entirely to positions within the furnace.

48. In a furnace wall, spaced tubes, and wall closure elements secured to the tubes and extending from positions on the furnace sides of 15 the tubes to positions on the opposite sides of the tubes, said elements presenting furnace faces forwardly and rearwardly of the center lines of the tubes.

49. A method of building a wall comprising, 20 arranging spaced supports in wall relationship, inserting wall closing elements between adjacent supports from positions exterior of the wall, turning those elements to inter-lock them with the supports, pivoting the elements, and then 25 exerting pressure on the elements to bind them into closely fitting relationship with the supports.

KENNETH NAPIER.
